UNITED STATES PATENT OFFICE.

CHARLES R. BRAWNER, OF LOS ANGELES, CALIFORNIA.

PARCEL-HOLDER.

1,185,763.

Specification of Letters Patent.

Patented June 6, 1916.

Application filed June 14, 1915. Serial No. 33,890.

To all whom it may concern:

Be it known that I, CHARLES R. BRAWNER, a citizen of the United States, residing at Los Angeles, in the county of Los Angeles and State of California, have invented a new and useful Parcel-Holder, of which the following is a specification.

This invention relates to improvements in parcel holders and resides in the provision 10 of a holder which is particularly designed for holding parcels and various articles securely upon automobiles and other vehicles.

The primary object of this invention is to 15 provide a holder of simple construction which may be quickly and easily attached to the running board or other suitable part of a vehicle or detached therefrom without the use of a wrench or other tool and which may 20 be easily and quickly adjusted to hold articles and parcels of different sizes.

An additional object is to provide effective means for adapting the holder for holding articles of different sizes, said means 25 being so constructed and arranged that it may be easily adjusted and locked effectively in adjusted position and as easily unlocked without necessitating the employment of a wrench or other tool.

30 The invention consists in certain novel features of construction and combinations, and arrangement of parts as will be more fully hereinafter described and pointed out in the claims.

35 Referring to the drawings: Figure 1 is a side elevation of the holder showing it in use and attached to the running board of a vehicle; and Fig. 2 is a top plan view of the holder.

40 Referring to the drawings by characters of reference, 1 designates a preferably flat bar designed to rest upon the running board A or some other suitable part of the vehicle to which the device is secured. One end of 45 the bar 1 is upturned and formed with an eye 2 adapted to receive a securing strap 3. The other end of the bar has formed integral therewith a depending L-shaped clamping member 4 which is designed to coöperate 50 with the bar 1 when the device is clamped upon the vehicle. One arm portion of this L-shaped member 4 is disposed in parallel relation to the bar 1 and at the free end of said arm portion is carried an adjustable 55 clamping screw 5. The screw 5 is formed with an enlarged head 6 designed to engage

the under face of the running board A so as to clamp the bar 1 upon the board. The other end of the screw is provided with an enlarged winged head 7.

Extending from opposite sides of the bar 1 at the end thereof which carries the member 4 are ears 8 which slidably receive the arms of a horizontal extensible U-shaped clamping member 9. The web portion of 65 this clamping member 9 is directed upwardly at right angles to the arm portions and forms an inverted U-shaped article engaging portion 10.

Formed on one longitudinal edge of the 70 bar 1 are a plurality of notches 11 which are designed to coöperate with a detent 12 which is carried on the free ends of one of the arms of the clamping member 9. The clamping member 9 is formed of spring 75 material and the detent 12 will quickly spring into locking position and may be easily withdrawn from such position. The detent is formed by bending the end of one arm right angularly.

80 In use, the device is clamped, as shown in Fig. 1, upon the running board A of a vehicle or upon some other suitable part not shown, and the article or articles to be held are placed upon the bar 1 and engaged with the upstanding portion 10 of the clamp 9. The clamp 9 may be extended so as to bring the portion 10 in engagement with the article upon the bar and after having been adjusted may be locked by means of the 85 notches 11 and detent 12, securely in position. The strap 3 is then passed over the article or articles and after being looped through the U-shaped upright member 10 is secured tightly upon the article or articles 90 by means of a buckle or other fastening 13.

With reference to the foregoing description and accompanying drawings, it will be seen that I have provided a holder which may be 95 securely attached to a vehicle and operated to effectively hold articles without necessitating the employment of a wrench or other tool as is necessary in cases where set-screws and the like are used and this is considered one of the most essential points of 100 my invention. By having the clamping member 4 integral with the bar 1, a durable and extremely rigid structure is provided and one which when clamped in position is not apt to become deranged or loosened by 105 the jars and jolts from the vehicle when the latter is in operation. The device is of

such simple construction that it may be easily, quickly and cheaply manufactured and can be attached to various parts of vehicles of different characters.

In practice I have found that the form of my invention illustrated in the drawings and referred to in the above description as the preferred embodiment is the most efficient and practical, yet realizing that the 10 conditions concurrent with the adoption of my device will necessarily vary, I desire to emphasize the fact that various minor changes in construction, proportion and arrangement of parts may be resorted to 15 when required without sacrificing any of the advantages of my invention as set forth in the appended claims.

I claim:

1. A parcel holder comprising a bar, 20 means to secure the bar horizontally to a vehicle, ears formed on opposite sides of the bar at one end thereof, a resilient U-shaped clamping member having its side arms slidably mounted in the ears and lying parallel 25 to the side edges of the bar, an article engaging portion carried by the U-shaped member, said bar having a series of notches on one longitudinal edge thereof, and an inwardly extending detent carried on the free 30 end of one of the arms of the U-shaped member and engaging in the notches.

2. A parcel holder comprising a flat bar having notches formed on one side edge

thereof, means to secure a bar horizontally to a vehicle, ears formed on one end of the 35 bar on opposite sides thereof, a resilient U-shaped clamping member having its side arms slidably mounted within the ears and lying parallel to the side edges of the bar, an upright article engaging portion carried by the U-shaped clamping member, the other end of said bar being turned upwardly and formed with an eye, a holding element secured to the article engaging portion and eye, and an inwardly right-angularly extending portion formed on the free 40 end of one of the arms of the U-shaped member and engaging in the notches of said bar.

3. A parcel holder comprising a bar, 50 means to secure the bar to a vehicle, said bar having notches on one side edge thereof and intermediate its ends, a resilient expandable clamping member including parallel side arms, ears formed on one end of the 55 bar and slidably receiving said arms, and a detent carried on one of the arms at the free end thereof and engaging in the notches in the bar.

In testimony whereof, I have hereunto set 60 my hand at Los Angeles, California, this 24th day of May, 1915.

CHARLES R. BRAWNER.

In presence of—

CHAS J. CHUNN,
L. BELLE WEAVER.
